UNITED STATES PATENT OFFICE.

THOMAS E. WOOD, OF GREAT FALLS, MONTANA, ASSIGNOR TO WOOD & SAFFORD MACHINE WORKS, OF GREAT FALLS, MONTANA, A CORPORATION OF MONTANA.

APPARATUS FOR MOLDING GREENSAND PISTON-CORES.

1,331,736.

Specification of Letters Patent. Patented Feb. 24, 1920.

Application filed March 27, 1919, Serial No. 285,407. Renewed November 25, 1919. Serial No. 320,463.

To all whom it may concern:

Be it known that I, THOMAS E. WOOD, a citizen of the United States, residing at Great Falls, in the county of Cascade and State of Montana, have invented certain new and useful Improvements in Apparatus for Molding Greensand Piston-Cores, of which the following is a specification.

My invention relates to apparatus for molding green sand, for forming cores adapted for use in molding engine pistons, particularly the pistons for internal combustion engines.

An important object of the invention is to provide apparatus of the above mentioned character so constructed that the several parts thereof are adjustable, for molding the green sand core in different sizes.

A further object of the invention is to provide means whereby the piston boss cores are detachable and adjustably connected with removable supporting rods, whereby piston boss cores of different shapes and sizes may be employed and may be located at points spaced at different distances from the end of the cylinder core.

A further object of the invention is to provide means whereby the length of the green sand core may be adjusted.

A further object of the invention is to provide apparatus of the above-mentioned character, which may be operated conveniently and rapidly.

Other objects and advantages of the invention will be apparent during the course of the following description.

In the accompanying drawings forming a part of this specification and in which like numerals are employed to designate like parts throughout the same;

Figure 1 is a central vertical longitudinal sectional view through apparatus embodying my invention;

Fig. 2 is a horizontal sectional view, taken on line 2—2 of Fig. 1;

Fig. 3 is a similar view, taken on line 3—3 of Fig. 1;

Fig. 4 is a longitudinal sectional view, taken on line 4—4 of Fig. 1;

Fig. 5 is a view similar to Fig. 1, with the inner pattern elements partly removed from the casing;

Fig. 6 is a perspective view of the removable pattern carrying bars;

Fig. 7 is a similar view of the pattern carrying bar, showing a different number of pattern rings secured thereto; and,

Fig. 8 is a perspective view of the head pattern.

In the drawings, wherein for the purpose of illustration is shown a preferred embodiment of my invention, the numeral 10 designates an outer cylindrical pattern casing, which may be vertically arranged in use, but the invention is in no sense restricted to this arrangement. The outer pattern casing 10 has both ends open, and is provided, as more clearly shown in Fig. 2, with a pair of longitudinal interior grooves 11, removably receiving pattern carrying bars or elements 12, adapted to slide longitudinally therein. There are preferably two of these bars, and they are provided with semi-circular skirt reinforcing patterns 13, rigidly secured thereto, by welding or the like, or they may be formed integral with the bars 12. The numeral 14 designates reinforcing rib patterns, which are preferably semi-circular and carried by the bars 12. These patterns 14 are preferably formed integral with the bars 12, but may be detachable if desired. In Figs. 1, 4, 5 and 6, I have shown one set of the patterns 14, while in Figs. 7, I have shown the bar 12 provided with two patterns 14, it being understood that two or more sets of these patterns may be employed, if desired.

The numeral 15 designates wrist pin boss patterns, which may be of any suitable shape or size. These patterns 15 are preferably provided with openings 16, receiving screws 17, adapted to have screw threaded engagement within selected openings 18, formed in the bars. It is thus seen that the patterns 15 are readily removable and may be longitudinally adjusted upon the bars 12 and connected therewith in adjustment at different longitudinal positions.

The numeral 19 designates ring reinforcement sleeve pattern which is slidably mounted within the outer casing pattern 10 to be adjusted longitudinally therein and removed therefrom. The sleeve pattern 19

is arranged near the lower end of the pattern 10 or at the upper end of the core. The bars 12 are preferably flush with the inner surface of the outer casing pattern 10, as indicated in Fig. 3, and therefore do not interfere with the insertion of the sleeve pattern 19, within the outer casing pattern 10.

The numeral 20 designates an end or head pattern, which is slidably mounted within the sleeve pattern 19, and is adjustable therein and adapted to be removed therefrom. The inner end of this head pattern 20 is closed by an end 21, the pattern 20 being preferably hollow. The end 21 carries internal reinforcing rib patterns 22, which may be formed integral therewith, and the head pattern is further provided with a pair of longitudinal slots 23 for receiving longitudinal internal reinforcing rib patterns 24. These rib patterns are arranged to contact with the fore-shortened ends of one pattern 22 and contact with the boss patterns 15, thereby forming longitudinal internal reinforcing ribs in the molded piston which connect the piston bosses and the head of the piston. The patterns 24 may be removed from the grooves 23.

30 The operation of the apparatus is as follows:

With the elements of the apparatus assembled as shown in Fig. 1, the green sand may be introduced into the same and suitably tamped. The apparatus may be supported by placing the hollow head pattern 20 upon a post or upright, and after this tamping action, the outer casing pattern 10 may be moved downwardly with respect to the inner pattern elements, as indicated in Fig. 5. This downward movement of the outer casing pattern element may be continued until it has moved downwardly beyond the lower ends of the bars 12. The bars 12 and the pattern elements carried thereby may now be removed from the green sand core. The ring reinforcement sleeve pattern 19 may now be moved downwardly with relation to the head pattern 21, thereby separating these elements, and leaving the green sand core entirely supported by the head pattern 20. The patterns 24 may now be removed from the head pattern 20. The green sand core is now removed from the head pattern and may be placed within the mold, of the desired diameter. The casting of the cylinder will then proceed in the usual manner. The diameter of the piston cast will be regulated by the diameter of the mold, while its length will be controlled by the adjustment of the head pattern 20 within the pattern 19.

It is to be understood that the form of my invention herewith shown and described is to be taken as the preferred example of

the same, and that various changes in the shape, size, and arrangement of parts may be resorted to without departing from the spirit of my invention or the scope of the subjoined claims.

Having thus described my invention, I claim:

1. In apparatus of the character described, an outer pattern casing provided with longitudinal grooves, bars slidable 70 within the grooves, and wrist pin boss patterns carried by the bars.

2. In apparatus of the character described, an outer pattern casing provided with longitudinal grooves, bars slidable 80 within the grooves, and wrist pin boss patterns detachably connected with the bars.

3. In apparatus of the character described, an outer pattern casing provided with longitudinal grooves, bars slidable 85 within the grooves, and wrist pin boss patterns adjustably connected with the bars.

4. In apparatus of the character described, an outer pattern casing provided with inner longitudinal grooves, bars adjustably mounted within the grooves, and 90 patterns carried by the bars.

5. In apparatus of the character described, an outer pattern casing, patterns arranged therein, and supports for the patterns having adjustable connection with the outer pattern casing.

6. In apparatus of the character described, an outer pattern casing, bars arranged therein and adapted to be longitudinally adjusted with relation thereto, patterns carried by the bars, a ring reinforcement sleeve pattern longitudinally adjustably mounted within the outer pattern casing and disposed inwardly of the bars, and 105 a head pattern for the outer pattern casing.

7. In apparatus of the character described, an outer pattern casing, supporting elements arranged therein and adapted to move longitudinally with relation thereto, 110 patterns carried by the supporting elements, a ring reinforcement sleeve pattern longitudinally movably mounted within the outer pattern casing, and a head pattern longitudinally movably mounted within the 115 ring reinforcement sleeve pattern.

8. In apparatus of the character described, an outer pattern casing, wrist pin boss patterns arranged within the outer pattern casing and adapted to move longitudinally with relation thereto, a ring reinforcement sleeve pattern longitudinally movably mounted within the pattern casing, and a head pattern longitudinally movably mounted within the ring reinforcement sleeve pattern.

9. In apparatus of the character described, an outer pattern casing, wrist pin boss patterns adapted to be arranged within the outer pattern casing, a head pattern 130

movably mounted within the outer pattern casing and provided with longitudinal grooves, and longitudinal internal reinforcing rib patterns arranged within the 5 grooves and extending to the wrist pin boss patterns.

10. In apparatus of the character described, an outer pattern casing, wrist pin boss patterns adapted to be arranged within the outer pattern casing, a head pattern longitudinally movably mounted within the outer pattern casing and provided at its end

with transverse reinforcing rib patterns and having longitudinal grooves, and longitudinal internal reinforcing rib patterns 15 arranged within the grooves and extending longitudinally of the outer pattern casing.

In testimony whereof I affix my signature in presence of two witnesses.

THOMAS E. WOOD.
